UNITED STATES PATENT OFFICE.

CLINTON S. MESSLER, OF BEACON, NEW YORK, ASSIGNOR TO THE GREEN FUEL ECONOMIZER COMPANY, OF BEACON, NEW YORK, A CORPORATION OF NEW YORK.

AUTOMATIC SAFETY SYSTEM FOR VESSELS CONTAINING LIQUID UNDER PRESSURE.

Application filed May 24, 1924. Serial No. 715,552.

This invention relates to temperature and pressure control for vessels in which liquids are heated, and its chief object is to provide for the purpose automatic means of simple and durable construction which will operate with unfailing reliability, thus obviating all danger of explosion due to excessive temperature. In its preferred form the invention is designed for use with vessels, normally closed from the atmosphere, through which a continuous flow of liquid is maintained so as to be heated during its passage through the vessel, and in this class of apparatus the invention finds important application to fuel economizers for heating boiler feed-water. One form of the invention as designed for this purpose is illustrated in the accompanying drawings, in which

Fig. 1 shows the control system in a somewhat diagrammatic manner.

Fig. 2 is a section illustrating a relief valve which can be used in my invention.

Fig. 3 is a section illustrating a thermostatic valve suitable for my invention.

Fig. 4 is a diagrammatic side view, partly in longitudinal section, showing a steam boiler and a fuel economizer for heating the boiler feed-water.

In the system illustrated in Fig. 4 the gases or products of combustion from the boiler furnace 1 are conducted by a flue 2 to the economizer 3, comprising vertical water tubes 10 connected by transverse headers 11 to upper and lower longitudinally extending manifolds 4. Having given up a portion of their heat to the water in the economizer the furnace gases pass to the stack 5. Hot water is delivered from the economizer to the boiler by pipe 12, having a hand-valve 13, and the usual check valve 6, employed in all economizer systems, to prevent flow of water or steam from the boiler to the economizer. Water is supplied to the economizer from any suitable source, not shown, by a pump 7. The connection between pipe 12 and the economizer may be conveniently made, for the purpose of the present invention, through a pair of T's 14, 15. The first mentioned T houses a thermostat 16, of any suitable type, which extends into the T and is therefore subjected at all times to the temperature of the water leaving the economizer. The other T 15, is connected by a valve 17, preferably of the

balanced type, and pipe 18, to the hot-well or other storage receptacle, not shown. A suitable type of valve 17 is shown in Fig. 2, in which the two valve disks 19 are fixed on the valve stem 20 which is urged upwardly, to lift the disks off their seats, by a spring 21. The stem is connected to a diaphragm 22 spanning a chamber 23 having an inlet 24 for fluid under pressure by which the tension of the spring may be overcome and the valve held closed, as will be readily understood.

The fluid pressure inlet 24 of diaphragm valve 17 is connected by a pipe 25 through a valve 26 to the fuel economizer outlet T 70 so that the outlet pressure in the economizer can be communicated to the diaphragm. The inlet 24 is also connected, by pipe 27 through a valve 28 to the steam line or other source of fluid pressure which may be utilized at will to apply pressure to the diaphragm for closing valve 17. The two valves 26 and 28 are preferably of the gate type, and are actuated by the same stem 29, which, for the purpose of control from a remote point, may be provided with a sheave 30 connected by a belt 31 to an actuating device (as for example a hand-wheel, not shown) located at a convenient position. These valves 26 and 28 are also assembled 85 for opposite operation, that is, so that as one is opening the other is closing, and vice versa.

The pressure exerted on the diaphragm 22 of valve 17 is controlled automatically 90 by the thermostat 16, and valve 32 actuated thereby in pipe 25. The thermostat may be of any suitable type, but I prefer one of the expansible fluid class, in which the expansion and contraction of a fluid in response to change of temperature is utilized to actuate a piston or equivalent device. Thermostats of this type are well known and further description thereof is therefore unnecessary. With such a thermostat it is 100 advantageous to make the valve 32 one of the piston-actuated balanced type, for example as illustrated in Fig. 3. In this figure the valve is normally held open by a spring 33, and is closed against the tension of the springs (which can be regulated by the threaded plug 34) by the stem 35 and piston 36 upon which the fluid pressure transmitted by the tube 37 from the thermostat 16 is exerted. The opening 38 through which the 110

stem works is sealed by the sheet metal bellows 39, hermetically joined to the piston at the top and to the valve casing at the bottom. The piston and bellows are housed 5 in a cylindrical casing 40. In the side of the valve casing is a vent 41, and in the stem 35 is a passage 42 which is brought into register with the vent when the valve is closed, thereby putting the diaphragm 10 chamber 23, Fig. 2, into communication with the atmosphere, as will be readily understood.

The system illustrated operates as follows: Under normal conditions water from 15 the economizer (heated in its passage therethrough) is flowing to the boilers by way of pipe 12, valve 28 is closed and valves 26 and 32 open. The pressure in the economizer is therefore transmitted through pipe 25 to the 20 valve diaphragm 22 and valve 17 is held closed. If, now, the temperature in the economizer rises above the predetermined point (the thermostat being properly adjusted) at which vaporization in the economizer becomes dangerous the valve 32 closes. This cuts off the pressure on valve diaphragm 22, Fig. 2, and vents the diaphragm 25 chamber 23 to the atmosphere by way of passages 41 and 42, Fig. 3, thereby relieving 30 the pressure on the diaphragm and permitting spring 21 to open valve 17. Pipe 18 to the hot-well is thus opened, and through it the economizer is vented, reducing the pressure therein at once and at the 35 same time allowing more water to flow through it, which in turn reduces the economizer temperature. On the other hand, assuming the conditions to be normal, as first described, suppose that the economizer 40 pressure is reduced below the point necessary to keep valve 17 closed, as may happen if the pump (not shown) which passes water through the economizer, should stop. Valve 17 then opens, and vents the economizer to 45 the atmosphere through pipe 18 as previously described. The economizer then becomes an open vessel, and generation of steam therein cannot raise the pressure to the danger point. Valve 17 having been 50 opened by increase of temperature or decrease of pressure in the economizer, it cannot be closed again except by a manual operation, thus making it certain that the condition of the apparatus will be brought 55 to the attention of the attendant. To close valve 17 the sheave 30 is rotated, closing valve 26 and opening valve 28. The latter then admits sufficient pressure (from the steam line, for example) to diaphragm 60 chamber 23 to close the valve against the tension of spring 21. When it is judged that the economizer pressure has been restored to normal the valve 28 is closed and valve 26 opened, thereby restoring the system to normal condition. If, however, the

economizer pressure had not reached a value high enough to keep valve 17 closed, the latter is at once opened again as already described. Similarly, the same thing happens if the economizer temperature has not been reduced to normal, as will be readily understood, since valve 32 will not have been opened and hence the economizer pressure through pipe 25 cannot be transmitted to the diaphragm. The usual economizer safety 75 valve is indicated at 43.

It is to be understood that the invention is not limited to the specific construction herein illustrated and described, but can be embodied in other forms without departure 80 from its spirit.

I claim—

1. The combination with a normally closed container for heating a liquid, of a relief valve therefor, automatic means for 85 opening the relief valve, means for utilizing the internal pressure of the container to hold the relief valve closed in opposition to said automatic means, and temperature-controlled means operable independently of the 90 level of the liquid in said container for disabling said pressure utilizing means when the internal temperature of the said container rises to a predetermined point.

2. The combination with a normally closed container for heating a liquid, of a relief valve therefor, a spring under tension 95 to open the valve, pressure-actuated means to close the valve against the tension of said spring, a pipe connecting the container with the pressure-actuated means for actuation thereof by the internal pressure of the container, a normally open valve in said pipe, and thermostatic means responsive to the 100 temperature in the container for closing said normally open valve whereby the pressure on the relief valve closing means is cut off.

3. The combination with a normally closed container for heating a liquid, of a relief valve for the container, means tending to hold said relief valve open, and means arranged to operate above a predetermined pressure and below a predetermined temperature in the container to overcome the 110 first mentioned means and hold the valve closed.

4. The combination with a normally closed container for heating a liquid, of a relief valve for the container, automatic 115 means for opening the relief valve, pressure operated means for utilizing the internal pressure of the container above a predetermined value to hold said relief valve closed in opposition to said automatic means, and means for cooperating with said pressure operated means for closing the relief valve after the same has been opened by said automatic means, said means for cooperating 120 including a manually operable member.

5. The combination with a normally closed container for heating a liquid, of a relief valve therefor, automatic means for opening the relief valve, means for utilizing the internal pressure of the container to hold the relief valve closed, temperature-controlled means for disabling said pressure utilizing means when the internal temperature of the said container rises to a predetermined point, and means for cooperating with said pressure operated means for closing the relief valve after the same has been opened by said automatic means, said means for cooperating including a manually operable member.
6. The apparatus described in claim 2, in combination with manually controlled means for applying pressure from an external source to the pressure-actuated means, whereby to close the relief valve after the same has been opened by the spring.
7. The apparatus described in claim 3, in combination with means for closing the relief valve, the last mentioned means including a manually operable member.
8. The combination with a fuel economizer having a water outlet, of a relief valve connected with the said outlet, means tending to hold said relief valve open, and means arranged to operate above a predetermined pressure and below a predetermined temperature in the economizer to overcome the first mentioned means and hold the valve closed.
- 35 9. The combination with a fuel econo-
- mizer having a water outlet, of a relief valve connected with the outlet opening and having a spring under tension to open the valve, pressure-actuated means for closing the valve against the tension of the valve spring, a pipe connecting the pressure-actuated means with the economizer for actuation by the pressure therein whereby the relief valve is normally held closed but is permitted to open when the economizer pressure falls to a predetermined value, a normally open valve in said pipe, having means for venting the pressure-actuated means when the said normally open valve is closed, and thermostatic means responsive to the temperature in the economizer to close the normally open valve and vent the pressure-actuated means when the economizer temperature rises to a predetermined value.
10. The apparatus described in claim 9, in combination with manually controlled means for closing said pipe and applying pressure from an external source to said pressure-actuated mechanism.
11. In a system for the purpose described, in combination, a normally closed container for heating a liquid, a relief valve for the container, pressure-operated means to hold said valve closed, and means arranged to operate at a predetermined temperature to overcome the pressure-operated means and open said valve.

In testimony whereof I hereto affix my signature,

CLINTON S. MESSLER.
